FIRE HYDRANT

Edward Page, Walnut Creek, Calif., assignor to M. Greenberg's Sons, San Francisco, Calif., a corporation of California

Filed Dec. 22, 1965, Ser. No. 285

Term of patent 14 years

(Cl. D91—3)

FIG_1

FIG. 1 is a front view showing the fire hydrant of my invention;

FIG. 2 is a back view of FIG. 1;

FIG. 3 is a side view of FIG. 1, the side opposite thereto being a mirror image thereof;

FIG. 4 is a top view of FIG. 1; and

FIG. 5 is a bottom view of FIG. 1.

I claim:

The ornamental design for a fire hydrant, as shown and described.
